COMBINED METAL MOLD FOR CASTING
AND STRIPPING INGOTS

Septimus H. Griffiths, Canton, Ohio

Application July 18, 1936, Serial No. 91,421

5 Claims. (Cl. 22—139)

This invention relates to an improved and novel sectional mold for casting ingots from molten steel or other desirable molten metals, said mold being so designed as to constitute an ingot casting and self-stripping mold for producing large end up ingots and is composed of two sections, a major upper section and a lower minor section, with means for causing the upper section to be automatically and truly centered upon the upper face of the lower section at the point of juncture of the two sections.

The prime object of the invention is to provide a simple, novel, economical, practical and thoroughly efficient self-stripping mold that serves to prevent the formation of "piping or blow-holes" and to produce a solid ingot forming a homogeneous composition throughout.

Another object of the invention is to so form and construct a two section mold that the inner wall thereof will be inclined gradually from its top to its bottom in true alinement and of such dimensions as to produce an ingot having a smooth exterior surface, and that will effectually prevent the formation of a fin or fissure around its outer surface.

Another object of the invention is to so construct the two sections of the mold that the lower section will be fixedly secured to any suitable or desirable support to prevent its movement away from said support when it is desired to lift the upper section carrying the ingot away from said lower section, and to permit the self centering of the two sections of the mold when placing the sections together in readiness for the molding operation.

Further objects of the invention are to so construct my improved sectional mold that it will dispense with the use of plugs of all kinds and types that have been heretofore employed for closing the open bottoms of the mold and for lifting the ingot from the mold; to dispense with inverted stripping of the mold; to eliminate the employment of costly plungers and other equipment heretofore employed for forcing the ingot out of its mold, and to form a mold that is self-stripping, thereby saving time, labor, fuel and expense, and to materially increase the number of ingots produced within a certain period of time and at the same time improve the quality of the ingot product.

The foregoing and such other objects as may appear from the ensuing description are attained by the combination, arrangement, location and construction of the several parts hereinafter more fully described, illustrated in the accom-

panying drawing, and particularly pointed out in the claims appended hereto, it being understood that slight changes in the precise shape, proportions and minor details of the construction may be resorted to without departing from the spirit or sacrificing any of the advantages of the invention.

In the accompanying drawing forming a part of this specification it will be seen that:

Figure 1 is a side elevation of the type of mold embodying my invention, showing by dotted lines the formation of the inner wall thereof.

Figure 2 is a side elevation of the large upper section of the mold, showing it partly in section, and showing in full lines the projected end of the ingot when seated upon its support.

Figure 3 is a view partly in section and partly in elevation, showing the ingot stripped from the inner wall of the large upper section with the upper end of the ingot projected above the upper end of said section with the lower end of the section seated on its support, and

Figure 4 is a detail vertical section taken in the plane of the dotted lines 4—4, Fig. 1, showing a portion of the upper section broken away with its lower end portion seated on the lower section and the means for locking the lower section to its support with the support broken away.

In the embodiment of my invention as illustrated it will be seen that the numeral 2 indicates the larger upper section of the mold formed with integral outwardly extended lugs or ears 3 at its upper end portion to which suitable lifting means are removably attached for lifting and moving the said section away from contact with the lower smaller section 4' of the mold, and the lower end of said larger section 2 is provided with a plurality of integral outwardly, downwardly and oppositely disposed laterally extended formations 5, each of the formations having its upper face beveled downwardly and outwardly at 6, then extended downwardly and terminating with a horizontally disposed lower face 7, the inner face 8 of each of said extensions being upwardly and inwardly beveled or inclined and terminating with a vertically disposed shouldered portion 9 terminating with the horizontally extended meeting face 10 forming the point of juncture with the upper face of the lower section, as shown in Figs. 2 and 4 of the drawing, while the lower section 4' is provided at its upper end with similar but upwardly extended and oppositely disposed integral formations 11 reversely beveled or inclined, as shown in Fig. 1, so that when it is desired to join the sections together it is simply

necessary to lower the upper section 2 until the lowermost beveled inner faces 6 of each of its downward extensions 5 overlap and engage with the upward and outer end portion of the lower section 4' while the same lowering movement of the section 2 simultaneously causes the inner face of the beveled upward extensions 11 formed at the upper end of said section 4' to overlap and engage with the lowermost outer end portion 10 of the section 2, and said section 2 by a further lowering thereof will be automatically guided to and properly and accurately centered upon the meeting face of the lower section by contact with the vertically disposed shouldered 15 portions forming a part of each of the laterally disposed extensions or formations 5 and 11, thus causing the meeting faces of the sections which are preferably so machined as to form a true, accurate and tight juncture of the said meeting 20 faces.

Both of the mold sections are preferably formed of cast iron and when united at the point of juncture the inner wall is inclined gradually inwardly from the top to the bottom thereof, terminating with a concaved solid bottom, said formation being provided for the production of "large end up" ingots; for eliminating and dispensing with the use of all types of plugs and 25 ingot lifters heretofore employed in connection 30 with molds for casting ingots.

By the construction of my improved form of large end up mold the molten metal assures progressive solidification from the bottom to the top of the ingot; serves to prevent the formation of 35 piping and blow holes, which is a prime factor to soundness and homogeneity; the production of a higher grade and quality of ingot possessing a smooth exterior surface and interior, and adds to the value and quality of the rolled product produced from the ingot.

It will also be readily perceived that by this specially designed type of mold there is no fastening means employed to lock the sections together, hence neither time nor labor is required 45 for unlocking or releasing such fastening means, since the larger section or member is simply lowered and is automatically guided by the afore-said beveled extensions until the meeting faces truly and smoothly contact with and are held 50 truly in their properly aligned position by the vertically disposed shouldered portions at the point of juncture. By this particular construction of mold the two sections are intended to have special proportions or inside capacities with 55 relation to each other, that is, the lower section has a standard capacity for the reception of one-fifth only of the entire inner capacity of the mold for the reception of the molten metal, since it has been successfully demonstrated that such standard capacity of the smaller lower section of the mold prevents the possibility of a fin or fissure forming around the ingot at the point of juncture of the two sections, for the reason that when 60 pouring fluid steel at a temperature of 2850 to 2900° F. into a comparatively cold metal mold, which is usually about 400° F. in good practice, from an elevation of about seven feet, the average mold being seventy-two inches in height, when the hot metal strikes the bottom portion 65 of the mold or inside face thereof a skim, scum or film is immediately formed, owing to contact of the extremely hot fluid metal with the cold mold causing a splash or spray of the hot metal to radiate by the forced contact with the bottom 70 portion of the minor section, hence the absorption 75

of the extreme heat by contact with the cool body of said section promptly forms a solidification of sprayed portions of the metal in the nature of a scum or film that rises above the point of juncture of the sections, seals the juncture portion 5 of the mold, and thereby eliminates the formation of a fin or fissure of any type whatever around the outer surface of the ingot.

It will be seen that the lower minor section of the mold is seated upon a suitable support 13, 10 and is provided on each opposite side thereof at its lower end portion with an integral projected lug or ear 12 for the reception of an elongated metal link 14, said link being adapted to be swung over a fixed lateral extension 15 having 15 an upward and inwardly beveled or inclined surface 16 for the reception of the lower portion of the link 14, said link and extensions serving to maintain the lower section of the mold in fixed position with relation to its support, while the 20 major section of the mold carrying the entire ingot is lifted up and moved away to another position and seated upon its support 17, it being readily obvious that the same suitably extended support may be employed for the molds while 25 being charged with molten metal, and for the mold stripping operation.

When it is desired to strip the ingot from the mold the upper larger section carrying the entire ingot is lifted from the lower section with 30 the solid convexed lower end of the ingot projected below the lowermost face of said larger section and is moved to another position over and seated upon a suitable support with the projected, lower concaved face of the ingot seated 35 upon the upper face of the support, so that when the ingot is seated upon its support it will cause the automatic gravitation of the large heavy upper section until its projected lowermost faces 1 are caused to assume the position shown in 40 Fig. 3 of the drawing, said automatic action simultaneously causing the ingot to be forced and stripped away from the inner wall of the mold and cause the upper end of the ingot to be projected above the upper end of the mold section, 45 when the usual means employed for the purpose in ingot foundries is used to grip said upper projected portion of the ingot and convey it away to the soaking pit, heating furnace or other desirable destination, thereby facilitating and 50 simplifying the rapid stripping of ingots by the use of sectional molds of the type hereinbefore referred to.

It will be understood that this construction of mold is adapted for use in connection with all 55 kinds of molten metal for casting ingots or slabs, especially with relation to what is commonly known in the art as rimming or effervescent steel. Further, it will be seen that the extensions 6 formed on the lower end portion of the major 60 section 2 serves as a rest therefor, and also serve to prevent contact of its meeting face with any foreign matter that may accumulate on the support, adhere to its said face, and thereby tend to prevent a true and accurate joint at its point 65 of juncture with the minor section of the mold.

Having thus described my invention, what I claim and desire to secure by Letters Patent is:

1. A metal mold for casting self-stripping ingots, comprising an upper major section having 70 an integral oppositely disposed beveled and shouldered downward extension projected below its meeting face at two sides thereof, a minor lower section provided with an integral oppositely disposed reversely beveled and shouldered exten- 75

sion at two sides thereof projecting above its meeting face between the extensions of the major section, with the said shouldered portions of the major section overlapping and in contact with the outer wall of the upper end of the minor section, while the shouldered portions of the minor section contact with and overlap the lower outer wall of the major section, all of said extensions coacting simultaneously and jointly serving to automatically guide, center and maintain the meeting face of the sections into true alinement between the shouldered portions of said extensions at the point of juncture and to form a tight joint at the said point.

15 2. A metal mold for casting self-stripping ingots, comprising a major upper section provided with an integral downwardly disposed extension at opposite sides thereof projected below the meeting face of the section and formed with an inwardly and upwardly beveled face, a lower minor section having an integral lateral extension at its opposite sides projected above its meeting face with the inner face of the extensions beveled inwardly and downwardly, a support for the mold disposed below said sections, means for fixedly securing the minor section to the mold support, consisting of two integral and oppositely projected formations near the bottom of said minor section for the reception of one end portion 30 of an elongated metal link, and a laterally extended fixed member at each side of the mold support, so that the said link may be easily swung over the said fixed members, thereby fixedly securing the minor section to the support.

35 3. A metal mold for casting self-stripping ingots of the character described, comprising two sections horizontally separated, a mold support disposed below said sections, an upper major section formed so as to carry the entire ingot when lifted away from the other section, a minor lower section for forming a lower convexed end to the ingot, means secured to the minor section and the mold support for fixedly securing said minor section to the support, integral outwardly 40 extended lugs formed at the top portion of the major section for lifting the major section away from the minor section, said major section carrying the entire ingot with the lower convexed end of the ingot projecting below the lowermost end of said major section, and seating said convexed end of the ingot upon the support, thereby owing to the structural formation of the inner wall of the major mold section with relation to the outer wall of the ingot causing the major section only

to gravitate and be seated upon the support simultaneously forcing and stripping the ingot from the inner wall and project the upper end of the ingot above the top of the major section.

4. A metal mold for casting self-stripping ingots of the character described, comprising two sections horizontally separated, a mold support for said sections, an upper major section having a plurality of downwardly extended portions at its lower end and formed so as to carry the entire ingot when lifted away from the other section, a minor lower section for forming a solid convexed lower end ingot, means secured to the minor section and to the mold support for fixedly securing said minor section to the support, the minor section having only one-fifth of the inner capacity of the entire mold, outwardly extended lugs formed at the upper portion of the major section for lifting it away from the minor section and seating the convexed lowermost end of the ingot upon the support, whereby the structural formation of the inner wall of the major mold section with relation to the outer wall of the ingot causes the said major section only to gravitate and be seated upon the support simultaneously forcing and stripping the ingot from said inner wall and project the upper end of the ingot above the upper end of the major section.

5. A metal mold for casting self-stripping ingots comprising two sections horizontally separated, a major upper section and a minor lower section, said minor section being formed with a concaved solid bottom to form a convexed lowermost end to the ingot, a support for the mold disposed below both sections, means secured to the lower section and to said support for fixedly securing said lower section to the support, outwardly extended lugs formed at the top portion of the major section for lifting it away from the lower section, said major section being formed so as to carry the entire ingot away from the lower section with its lower end portion projecting below the bottom of the major section, and seating the lowermost concaved end portion of the ingot on the support, which owing to the structural formation of the inner wall of the major section with relation to the outer wall of the ingot will cause the major section only to gravitate until seated upon the support and simultaneously strip and force the ingot away from said inner wall of the said section and project the upper end of the ingot above the top of the major section.

SEPTIMUS H. GRIFFITHS.
